CLAIM

The ornamental design for an attache case for disks, as shown and described.

DESCRIPTION

FIG. 1 is a perspective view of an attache case for disks showing my new design in a closed condition;

FIG. 2 is a left side elevational view thereof, the right side being a mirror image thereof;

FIG. 3 is a front elevational view thereof;

FIG. 4 is a rear elevational view thereof;

FIG. 5 is a bottom plan view thereof;

FIG. 6 is a top plan view thereof;

FIG. 7 is a perspective view thereof in open condition and without disk supports;

FIG. 8 is a perspective view thereof with disk supports added;

FIG. 9 is a perspective view of an attache case for disks showing a modified form of the interior of my new design with supports added;

FIG. 10 is a perspective view of an attache case for disks showing another form of the interior of my new design with supports added.
